ATTORNEY.

UNITED STATES PATENT OFFICE.

VICTOR LEATON OCHOA, OF NEW YORK, N. Y., ASSIGNOR OF ONE-HALF TO
BENJAMIN A. JACKSON, OF NEW YORK, N. Y.

PEN OR PENCIL CLIP.

No. 854,878.

Specification of Letters Patent.

Patented May 21, 1907.

Application filed May 3, 1906. Serial No. 315,001.

To all whom it may concern:

Be it known that I, VICTOR LEATON OCHOA, a citizen of the United States, residing at New York, in the county of New York and State of New York, have invented certain new and useful Improvements in Pen or Pencil Clips, of which the following is a specification, reference being had therein to the accompanying drawings.

10 My invention relates especially to devices employed for holding fountain pens, pencils, thermometers, etc., in place in the vest pocket, when not in use, thus preventing accidental loss, breakage from dropping, or displacement through the stooping of the person, or when the garment is removed, and has for its object the provision of a simple, cheap and effective holder, which will automatically engage the edge of the pocket when the 15 pen or pencil is placed therein, and which will readily adapt itself to any diameter of pen or pencil, and to any longitudinal position thereon.

To attain the desired end, my invention 20 consists essentially in certain new and useful combinations or arrangements of parts, and peculiarities of construction, all of which will be hereinafter first fully described, and then pointed out in the claim.

25 In the drawing, Figure 1 is a side elevation of a holder embodying my invention, and Fig. 2 is a front elevation of the same shown as applied to a fountain pen.

Like letters of reference, wherever they occur, indicate corresponding parts in both figures.

30 In forming my improved holder, a loop of piano wire, or the equivalent, is made by

bending the wire, as at *a*—*a*, and then bending the two extremities above the loop, commencing with a sharp bend, *b*—*b*, spirally, in a plurality of convolutions *c*—*c*—*c*—*c*. When thus formed, the convolutions of the spring will embrace a pen, pencil, thermometer, or the equivalent, with sufficient pressure to 45 maintain any desired longitudinal position thereon, and such convolutions will adapt themselves to various diameters, as required. The downwardly-projecting tongue or loop will readily pass over the top of a pocket, 50 such action being automatic when the pen or pencil is pushed down within the pocket, and will permit the removal of the pen or pencil without any manipulation of the loop, and the device can be readily adjusted to any 55 length of pen or pencil or moved as a pencil is shortened by use, in accordance with the depth of the pocket. As the loop is smooth, and formed of round material, the edge of the pocket will not become worn or abraded. 60

Having now fully described my invention, what I claim as new therein and desire to secure by Letters Patent, is:

As a new article of manufacture, a pen or pencil clip consisting of a loop of wire, the 65 looped portion bent to constitute a tongue, the remaining portions of the wire being wound to form a double spiral spring, substantially as shown.

In testimony whereof I hereto affix my signature in presence of two witnesses.

VICTOR LEATON OCHOA.
